HELICAL ELECTRIC IMMERSION HEATER

Percy B. Levitt, Millburn, N. J., assignor to Cities Service Oil Company, New York, N. Y., a corporation of Pennsylvania

Application July 17, 1943, Serial No. 495,171

8 Claims. (Cl. 219—38)

This invention relates to improvements in helical electric immersion heaters used for the heating of motor oils in the crankcases of aircraft and other motor vehicles used at extremely low temperatures.

Electric heaters have been used to considerable extent for heating such motor oils, and it has been the general practice to make such heaters by winding an electric resistance wire in a helix around a refractory core, the windings being uniformly spaced along the core. However, one of the difficulties encountered in the manufacture and use of such heaters was to obtain the desired wattage rating for the heater and at the same time provide a heater that would have a useful life of reasonable length. It was found that heaters with uniform windings gave such high temperature difference along the winding that very coarse wire had to be used to get a reasonable life from the heater. On the other hand, it was difficult with such coarse wire to get the required resistance out of the space available. It was further found that the use of fine wire, which would give the desired resistance, would also fail very quickly because of the high local temperatures developed where the windings were uniformly spaced.

After considerable trouble with helical electric heaters, a heater winding was developed in which the heat input per increment of length matched the heat dissipation along the heater. This resulted in a heater in which the windings of the resistance wire were arranged so that the spacing in the intermediate section of the heater were considerably greater than at the ends of the heater, and one in which the high local temperatures previously encountered were no obtained. It was also found that fine resistance wire could be used in the new heater without approaching the failure temperature of the wire and that with this new heater one could obtain a much higher load than with a similar heater having uniformly spaced windings. Also in the manufacture of the improved heater of the present invention, the construction of the heaters was greatly facilitated by providing a grooved core with the grooves spaced so as to give the particularly desired distribution along the length of the heater. The improved electric heater of the present invention has other features and advantages which have contributed to its successful use.

The primary object of the invention is to provide an improved helical electric immersion heater in which the windings are so distributed as to

match the dissipation characteristic and avoid the production of localized high temperatures.

A further object of the invention is to provide a helical electric immersion heater in which the 5 windings are so distributed as to permit the use of resistance wire of smaller gauge than otherwise would be possible and still avoid reducing the overload capacity of the heater.

A further object of the invention is to provide 10 an improved refractory core for helical electric immersion heaters which will greatly facilitate the winding of the resistance wire in a predetermined spaced relation.

The improved heater of the present invention 15 will be described more in detail hereinafter in connection with the accompanying drawing forming a part of this application.

In the drawing:

Fig. 1 is a side view of a heater constructed in 20 accordance with the features of the present invention with certain parts in section and other parts broken away.

Fig. 2 is a chart showing temperature curves of the improved heater of the present invention 25 and a temperature curve obtained from a similar heater having uniformly spaced windings.

The improved heater of the present invention as shown in Fig. 1 of the drawing, comprises an outer metal casing or sheath 10 which preferably 30 is cylindrical, but may be of any desired uniform cross section, and constructed of some metal of relatively high conductivity, such as "Duralumin," aluminum, copper, brass, or other suitable metal or alloy. The outer surface of casing 10 may be plain or provided with radial or longitudinal fins, grooves or channels. The casing 10 encloses a cylindrical cast refractory core 12 which is preferably made of zircon and provided with parallel helical grooves 14 and 16 in which 35 are laid a resistance heating wire 18. The wire may be of chromium, nickel, chromium alloy, aluminum-cobalt-iron alloy or other suitable composition. The resistance wire 18 is a looped resistance in which two parallel strands of the wire 40 beginning with the loop at the left hand of the core is laid in parallel, respectively, in the grooves 14 and 16. At the right hand of the core, the resistance wire windings terminate in leads 20 and 22 which extend through a neck section 24 which is provided with a shoulder and end thread, as shown, for mounting the heater.

The core 12 is of uniform section and preferably cast from a zircon mix, with the grooves 14 and 16 arranged so that the heat input per increment of length matches the heat dissipation,

resulting in a spacing in the intermediate or mid-section of the core for a considerable distance (about $\frac{1}{2}$ its length) of approximately twice that at the current-supply end of the heater, with the spacing at the opposite end being nearly the same as that at the current-supply end but slightly wider, as shown in the example. It will be noted that the spaces between windings from either end toward the central section of the heater are gradually wider. The looped resistance wire with parallel windings is preferred but the heating unit may be made by spacing a single resistance wire wound in a helical groove around the outside of the core to give the desired heat input characteristic, the core preferably being hollow so that a lead wire may extend from the left hand end of the core through the core and to the current inlet end at the right.

In the structure shown in Fig. 1, the resistance wire is looped through a hole connecting the ends of the grooves 14 and 16 and then wound on the core by a special winding machine. Before the core and resistance wire thereon are inserted into the casing 10, the unit is coated with a zircon wash made of 50% milled grain zircon, 50% natural grain zircon bonded with a mixture of 6% P_2O_5 and 2% of chromic acid. This coating is hardened onto the wire and the core by heating the unit to a temperature of about 600° F. in an oven. The resulting coated heating unit is centered in the casing 10 and packed therein with a marginal layer of fine zircon sand 26 which is a good dielectric. The fine zircon sand is firmly packed into the casing around the heating unit by vibrating the casing as the sand is introduced. The electric resistance heating unit is finally sealed in the casing with a plug or head 28 which may be screwed or otherwise fastened in the end of the casing 10.

The full line curve in Fig. 2 labeled "Distributed winding" is a substantially flat temperature curve made by taking the temperatures with thermocouples along the heater resistance wire shown in Fig. 1, the width of the chart in Fig. 2 representing the length of the heater. The broken line curve labeled "Uniformly spaced winding" in Fig. 2 is a temperature curve made by similarly taking temperatures along the wire heater of the same size as that shown in Fig. 1, but in which the windings of the resistance wire were uniformly spaced. It will be noted that at no point does the temperature for the heater wire shown in Fig. 1 go above 900° F., whereas the temperature for approximately the mid-point of the heater wire of the uniformly spaced windings was between 1400° and 1500° F. (approx. 1450° F.). Furthermore, the temperatures at the ends of that heater went considerably below the corresponding temperatures for the heater of Fig. 1.

While the present invention is particularly directed to electric immersion heaters having a low diameter-to-length ratio, of Example 1 to 5, the invention may be applied to heaters of substantially different ratio. It is to be further understood that the heaters need not necessarily be circular in cross-section, but may be of some other convenient or desirable shape. The problems discussed, such as the high local temperatures in the heater wires, are particularly encountered in heaters having relatively short length compared to their width or diameter.

Having described the invention in its preferred form, what is claimed as new is:

1. In an electric immersion heater for heating lubricating oils in an oil container associated

with an internal combustion engine, the heater including a metal casing of relatively short length compared to its width, an electric resistance heating unit inside said casing arranged so as to supply heat to the metal casing and to heat the same to a substantially uniform temperature, an improved heating unit comprising a refractory core of insulating material having a circumferential helical groove of uniform diameter extending from end to end of the core, a resistance wire wound in said groove, the windings of the wire and the corresponding elements of the groove being spaced relatively close together at the end portions of the core and at relatively greater distances apart along the intermediate section of the core.

2. In an electric immersion heater having an elongated electric resistance heating element substantially surrounded by a tubular metal shell, an improved resistance heating element comprising a core of refractory insulating material having a uniform cross-section, and a helical electric resistance wire wound thereon from end to end of the core, the windings being spaced farther apart at the intermediate section of the core than at the ends and arranged so that the heat distribution along the heater will give a substantially flat temperature curve.

3. In an electric immersion heater having an elongated electric resistance heating unit substantially surrounded by a tubular metal shell, an improved heating unit comprising a core of refractory insulating material on which is wound a fine electric resistance heating wire in which the windings are of substantially uniform length and are arranged so that the spacings in the intermediate section of the heater are considerably greater than at the ends of the heater.

4. In an electric heater having a low length-to-diameter ratio, an improved resistance heating unit comprising a refractory core of insulating material having a fine helical resistance wire wound thereon and in which the resistance wire windings are of substantially uniform diameter and are arranged so that the spacings in the intermediate section of the heater are considerably greater than at the ends of the heater and also so arranged that a relatively flat temperature curve would be produced by taking the temperatures along the heater wire when in operation.

5. In an electric immersion heater having a low length-to-diameter ratio, an improved core of refractory insulating material and of substantially uniform cross-section having a spiral groove in its external surface and extending substantially the full length of the core, the convolutions of the groove being relatively closely spaced at the ends of the core and relatively widely spaced along its intermediate section.

6. In an electric immersion heater having a low length-to-diameter ratio and an elongated electric resistance heating element substantially surrounded by a tubular metal shell, an improved resistance heating element comprising a core of refractory insulating material having a uniform cross-section, and a fine helical electric resistance wire wound upon the core from end to end thereof, the windings being spaced farther apart at the intermediate section of the core than at the ends and arranged so the heat distribution along the heater will give a substantially flat temperature curve, thereby avoiding localized high temperatures in the heater.

7. An electric heater comprising a core having a resistance heating wire wound thereon in the form of a helix of uniform cross-section, the resistance wire windings being arranged so that the spacings in the intermediate section of the heater comprising approximately one half the total length of the heater are considerably greater than at the ends of the heater.

8. An electric heater having a helical electric resistance wire with windings of substantially 10

uniform diameter in which localized high temperatures in the wire are avoided, comprising a helical resistance wire in which the windings are spaced farther apart along the intermediate section of the heater than at the ends thereof and arranged so that the heat input per increment of length matches the heat dissipation of the heater at a predetermined substantially uniform temperature.
